UNITED STATES PATENT OFFICE.

JOSEPH W. SHARP, JR., OF BERWYN, AND ALBERT E. BACON, OF GERMANTOWN, PENNSYLVANIA, ASSIGNEES TO HAINES, JONES & CADBURY INCORPORATED, A CORPORATION OF PENNSYLVANIA.

FLUSHING DEVICE.

1,227,554.

Specification of Letters Patent.

Patented May 22, 1917.

Application filed February 24, 1910. Serial No. 545,569.

To all whom it may concern:

Be it known that we, JOSEPH W. SHARP, Jr., and ALBERT E. BACON, citizens of the United States, residents, respectively, of 5 Berwyn, county of Chester, State of Pennsylvania, and Germantown, county of Philadelphia, State of Pennsylvania, have invented a new and useful Flushing Device, of which the following is a specification.

10 Our invention relates to improvements in automatic flushing devices for water closets. The object is to provide an improved self-containing means for automatically flushing the closet. Our invention includes improved 15 means for conveniently securing the flushing device to a standard earthenware closet without requiring any changes in the construction of said closet, and so that all the parts of the flushing device shall be entirely 20 outside of the bowl of the closet.

Our flushing device is adapted to be secured to the earthenware closet so that the closet shall support the same to properly withstand the thrust and pressure of operating 25 the valve and also the pressure of the water. Our device is adapted to be located out of the way and yet readily accessible for inspection or repair, and also readily removed. Our device is adapted to be operated 30 with certainty in connection with the operation of the seat.

Our invention also comprises improvements in details of construction.

Referring to the drawings:—

35 Figure 1 is a plan view of our device with part shown in section.

Fig. 2 is a side elevation on a smaller scale.

40 Fig. 3 is a vertical section on line 3—3 of Fig. 1.

Similar numerals refer to similar parts throughout the several views.

In Figs. 1, 2 and 3, we show a device adapted to be secured to a closet having an 45 inlet opening in the top of the bowl. A convenient way of securing our device to the closet is to provide the extension 9 of body 7, which corresponds to the spud, with a threaded end, and a coöperating threaded 50 ring 8, a collar 10 and a rubber gasket 11. The gasket 11 is inserted in the opening of the closet and the threaded ring 8 is then moved toward ring 10 causing a compression of gasket 11, between rings 8 and 10, which 55 thickens the gasket, in a well known way,

and causes a tight fit within the opening of the closet. It will be noted that the main structure of body 7 has a horizontal extension and is provided with a downwardly extending nozzle 9 for engagement with the 60 closet and an upwardly extending nozzle 12 for engagement with pipe 13 leading to tank, 40, and a horizontally extending nozzle 14 for engagement with the supply pipe 15. The body structure 7 is provided with three 65 chambers as follows: chamber 16 connected with the closet, chamber 17 connected with the tank and inlet chamber 18 connected with the supply. The partition 19 separating chambers 16 and 17 is apertured and 70 provided with a valve seat 20 having a co-operating valve 21. The partition 22, separating chamber 17 from 18, is apertured and is provided with a valve seat 23 having a co-operating valve 24. Valve 21 is normally 75 held in the open position by the spring 25, while valve 24 is normally held in closed position by the compression spring 26. Connected with the valve 21 is the slide rod 27 which projects through a suitable packing 80 28 beyond the body member 7, and preferably carries at its free end an anti-friction ball device 29 for engagement with a contact plate 30 located on the back of the seat 31. This friction ball device 29 is secured 85 within the hollow casing 84 adjustably mounted on the end of rod 27 of which it forms a part and secured in place by set screw 85. The necessary movement of rod 27 to secure the required actuation of valves 90 21 and 24, and to take up wear, is thus secured. Secured to slide rod 27 and projecting in front of valve 21 is the rod 32 which is adapted to engage and project into a socket 33 of valve member 24. 95

The chambered extension or lug 84 of body member 7 is provided with the upwardly directed apertured lug 34. Supported above the bowl by the apertured standards 86 is the rod 36 forming a strut or brace for the 100 hinges 37, which, with standards 86, are secured thereto by pins 87. This construction permits the rotation of strut 36 in a horizontal plane, the axis of which passes through the apertures in hinges 37. The 105 bolt or brace 35 passes through strut 36 and lug 34. When the required position of adjustment between brace 36 and body 7 is secured bolt 35 is secured in position by nuts 38 and 39, thus maintaining the parts in said 110

position of adjustment and clamping brace 36 against movement upon the elevation or depression of the seat.

It should also be noted that the connections between body 7 and pipe 13, and supply pipe 15 are made with threaded coupling rings and ground joints so that they can be readily disconnected when it is desired to take the valve structure apart. By unscrewing the cap 65 valve 21 may be removed. It might also be noted that the spring 25 is confined between a washer 41 which engages with the slight annular projection 42 in the inside of body member 7, and with the ring or flange 43 at the other end, which may be integral with rod 27. On the other side of ring 43 from the spring may also be provided a washer of some soft material 44, for taking the jar of impact between ring 43 and plug 65, as the spring 25 normally holds this ring against the inner end of plug 65. The spring 26 controlling valve 24 is confined between the flange 45 of valve member 24 and the cap 46 which is threaded onto the end of the body portion 7. It will thus be seen that by removing plug 65 and cap 46 the two valves can be instantly removed for inspection or repair. By disconnecting the coupling rings 47 and 48, nut 39, and loosening ring 8, the entire valve structure can be removed.

The operation of the device is as follows:

Referring to Fig. 3, the several valves are held in position against the pressure exerted by springs 25 and 26 by seat member 31 when held down in the horizontal or operative position. When the seat member 31, is moved into the horizontal position the contact plate 30 presses against the anti-friction bearing 29 and forces the slide rod 27 in or to the right hand, closing the valve 21 onto valve seat 20. This movement of the slide rod 27 also forces the rod 32 and valve 24 with which it engages, into the open position. In these positions of the valves the water from a suitable source of supply under pressure, enters through pipe 15 and chamber 18, into chamber 17, and passes through pipe 13 to tank 40, filling said tank 40 until the same is under the same pressure of water as that of the source of

supply. Upon removing the weight from seat 31, the seat moves to the position shown in dotted lines in said Fig. 3, or in solid lines in Fig. 2, in response to the pressure exerted by the rod 27 actuated by spring 25. This movement of rod 27 in the left hand direction carries the valve 21 into open position and also permits the closure of valve 24 in response to actuation of spring 26. When valve 24 is closed the pressure of water from the source of supply coöperates with the pressure of spring 26 to maintain said valve 24 in the closed position. Valve 21 now being open, the water flows from tank 40 into chamber 17 thence to chamber 16, through spud 9, to the water closet, until the tank is empty. Upon closing the seat again the operation is repeated.

What we claim is:—

1. In combination with a water closet bowl and a hinged seat, hinge posts adapted to maintain the hinge axis at a point a substantial distance above the horizontal plane of the seat, a chambered body having water inlet and discharge apertures and a valve-controlled port therebetween, a spring-actuated seat actuating valve-controlling rod projecting from the chambered body, above the top of the bowl, and a strut engaged between the hinge posts and the chambered body, as and for the purpose specified.

2. In combination with a water closet bowl and a hinged seat, hinge posts supported on the bowl structure, said posts adapted to maintain the hinge axis above the horizontal plane of the seat, a chambered body outside the bowl structure, said body having water inlet and discharge apertures and a valve-controlled port therebetween, a spring-controlled valve and seat actuating rod projecting from the chambered body, a cross-rod between the hinge posts and a strut connected between said rod and the chambered body.

JOSEPH W. SHARP, JR.
